UNITED STATES PATENT OFFICE

145,327

DESIGN FOR AN APRON

Helene Pons, New York, N. Y.

Application February 26, 1946, Serial No. 126,930

Term of patent 3½ years

(Cl. D3—26)

To all whom it may concern:

Be it known that I, Helene Pons, a citizen of the United States of America, residing in New York city, county of New York, and State of New York, have invented a new, original, and ornamental Design for an Apron, of which the following is a specification, reference being had to the accompanying drawing, forming part thereof.

Fig. 1 is a front view of an apron showing my new design.

Fig. 2 is a rear view thereof.

I claim:

The ornamental design for an apron, substantially as shown.

HELENE PONS.
